UNITED STATES PATENT OFFICE

PAUL ARZET, OF SHELBYVILLE, INDIANA, ASSIGNOR TO THE KENNEDY CAR LINER & BAG CO., OF SHELBYVILLE, INDIANA, A CORPORATION OF INDIANA

SPECIAL PACKAGE

Application filed April 2, 1932. Serial No. 602,787.

This invention relates to special packages and particularly to a bag or receptacle for packaging finished laundry.

One of the objects of the invention is to provide a laundry receptacle having a relatively stiff bottom, flexible sides, and a relatively stiff independent insert in the form of an endless sided member adapted to be folded flat so that the empty receptacle with the insert inside may be stacked flat in bundles, for shipment.

Another object of the invention is the provision in a laundry receptacle as described, of the insert having re-entrantly folded ends which when folded out against the constraint of the flexible envelope, execute a toggle action past the dead center of the fold, so that the insert is maintained self-expanded, and in turn holds the flexible envelope open so that it can be conveniently packed with the various laundered articles.

Other objects of the invention will appear as the following description of a preferred and practical embodiment thereof proceeds.

In the drawing which accompanies and forms a part of the following specification, and in which the same characters of reference have been employed throughout the several figures to designate identical parts:

Figure 1 is a perspective view of the laundry bag or receptacle filled and sealed;

Figure 2 is a transverse vertical section;

Figure 3 is a fragmentary perspective view showing one of the re-entrantly folded ends in partially expanded position in broken lines, and in fully expanded position past dead center, in full lines;

Figure 4 is a perspective view of the receptacle, expanded but still open at the top and with parts broken away to show otherwise hidden parts; and

Figures 5, 6 and 7 show various stages in the folding of the laundry receptacle reducing it to the flat form in which it is shipped or transported when empty.

Referring now in detail to the several figures, the numeral 1 represents an envelope, the sides and ends of which are preferably of a suitable grade of flexible paper. The

bottom 2 is preferably a rectangular sheet of relatively stiff material, to which the lower margins of the sides and ends are attached as indicated at 3 in Figure 2, by pasting or in any other suitable manner. It is to be understood that while the receptacle is preferably parallelepipedal in shape, the particular shape of the receptacle is not to be considered as limiting the scope of the invention.

The envelope 1 is provided with a stiffening insert 4 comprising a strip of relatively stiff material having a width preferably less than the height of the envelope and formed into an endless band but having its adjacent ends brought together as indicated at 5 in Fig. 4, and pasted together by a suitable adhesive strip 6. The endless insert is preferably scored transversely so as to be foldable along lines adapted substantially to register with the corners of the bottom sheet 2, and the ends 6 and 7 of the insert are scored or otherwise constructed so as to be foldable re-entrantly as is indicated in broken lines in Figure 3. The insert is structurally independent of the envelope and may be taken out or folded flat and placed on its side in the envelope against the bottom thereof in order to form a flat package for shipment.

In the use of the receptacle, the insert is arranged to form sides and ends perpendicular to the bottom 2 and the re-entrantly folded ends are pushed outwardly, thrusting against the sides of the envelope 1 until finally the intermediate folds of said ends spring past the dead center and assume the full line position shown in Figure 3, in which position they automatically maintain the insert in open or expanded position, and the insert pressing against the envelope holds it open. The open position of the receptacle is shown in Figure 4, and it is obvious that articles of laundry, or for that matter, articles of any nature may be packed in the receptacle.

Figures 5, 6 and 7 show that the insert in its folded collapsed state may be laid on the bottom of the envelope, since the height of the insert is not greater than the width of the

bottom. The flexible envelope may be folded down in any convenient manner. Figure 5 shows that the middle portion of the envelope is held up-right, the side portions folding flat and convergent at the ends. The upright portion is then laid flat as shown in Figure 6, and together with the convergent ends is folded back upon the package in the manner indicated at 8. The flat folded portion is then folded in the reverse direction, bringing its free edge over the center of the package as shown at 9 in Figure 7. A number of these flat units may be bundled together and shipped as one package.

15 While I have in the above description disclosed what I believe to be a preferred and practical embodiment of the invention, it is to be understood that numerous changes in the construction and modification of the receptacle may be made without departing from the spirit or scope of the invention as claimed.

What I claim is:

1. Special package comprising an envelope of parallelepipedal shape having a relatively stiff bottom and relative flexible sides, and an endless insert forming a lateral lining for the lower part of said envelope, and folded so as substantially to register with the edges of the bottom, said insert being re-entrantly folded at its ends, said ends when opened within said envelope being adapted to execute a toggle movement against said envelope past dead center, thereby sustaining said insert and said envelope in open position.
2. Special package comprising an envelope of parallelepipedal shape having a relatively stiff bottom and relatively flexible sides, and an independent endless insert forming a lateral lining for the lower part of said envelope, and folded so as substantially to register with the edges of the bottom, said insert being re-entrantly folded at its ends, said ends when opened within said envelope being adapted to execute a toggle movement against said envelope past dead center, thereby sustaining said insert and said envelope in open position.
3. Special package comprising an envelope of parallelepipedal shape having a relatively stiff bottom and relatively flexible sides secured to the edges of said bottom as by pasting, and an endless insert forming a lateral lining for the lower part of said envelope, and folded so as substantially to register with the edges of the bottom, said insert being re-entrantly folded at its ends, said ends when opened within said envelope being adapted to execute a toggle movement against said envelope past dead center, thereby sustaining said insert and said envelope in open position.

In testimony whereof I affix my signature.

PAUL ARZET.
